UNITED STATES PATENT OFFICE.

CHARLES LYMAN, OF CLARINDA, IOWA.

BROODING-COOP.

1,081,847.

Specification of Letters Patent.

Patented Dec. 16, 1913.

Application filed October 18, 1909. Serial No. 523,212.

To all whom it may concern:

Be it known that I, CHARLES LYMAN, a citizen of the United States, residing at Clarinda, in the county of Page and State 5 of Iowa, have invented certain new and useful Improvements in Brooding-Coops; and I do declare the following to be a full, clear, and exact description of the invention, such as will enable others skilled in the art to 10 which it appertains to make and use the same.

This invention relates to improvements in coops for brooding hens.

The invention consists in the construction 15 and arrangement of parts, as will be hereinafter described and particularly pointed out in the claim.

In the accompanying drawings: Figure 1 is a vertical longitudinal section through a 20 brooding coop constructed in accordance with the invention taken on line 1—1 of Fig. 2. Fig. 2, is a horizontal section taken on the line 2—2 of Fig. 1. Fig. 3, is a vertical cross-section through the run or yard of the 25 coop looking toward the front of the house, and showing the door thereof in closed position and arranged to permit the chicks to leave and enter the house. Fig. 4, is a plan view of the house with the cover removed. 30 Fig. 5, is a vertical cross-section of the house on line 5—5 of Fig. 1; and Fig. 6, is a detail perspective view of the reversible door for closing the opening in either the house or the yard portion of the coop.

In the embodiment of the invention, I 35 provide a house 1, preferably formed of galvanized sheet metal and at the front of the house is arranged a yard or run 2. The sides of the run are preferably rigidly secured to 40 the sides of the house. The house 1 is formed of a series of sheet metal plates detachably secured together at the corners of the house by slip joints 3, which are formed by bending or folding the adjacent edges of 45 the sides, front, and rear sections of the house to form interlocking flanges, which, when slipped together, firmly but detachably secure said parts together.

On the upper edges of the sides and back 50 plates of the house are formed outwardly bent roof or cover retaining flanges 4, which are of sufficient width to contain a series of ventilating apertures, which are formed therein and are clearly shown in Fig. 4, of the drawings. The cover or roof 6, of the house, is provided on three of its sides with

inwardly bent flanges 7, which are adapted to be slipped into engagement with the outer edges of the apertured flanges 4, on the sides and back plates of the house, thus detachably securing said roof or cover in place. 60

By referring particularly to Fig. 4, it will be noticed that the construction described provides for the escape of the foul air from the house while preventing the entrance of 65 rain or snow and also facilitates the engagement and disengagement of the roof to the house.

The lower ends of the sides of the house are bent inwardly to form floor receiving 70 flanges 8, with which are engaged the floor 9, of the house. The floor 9, is preferably in the form of a tray, around the edges of which are upwardly extending flanges and to the bottom of which, adjacent to the rear 75 edge, is secured a handle 10, by means of which the floor may be removed from the house. In the front side of the house is formed a door opening 11, along the side edges of which are formed guide flanges 12, 80 with which are slidably engaged a reversible door 13. Below the door opening 11, is formed a row of ventilating apertures 11'. The door 13, has formed along its side edges inwardly bent flanges 14, which are adapted 85 to engage the guide flanges 12, thus slidably and detachably securing the door over the opening 11. In the door 13, adjacent to one end is formed a ventilating opening 15, covered by a wire screen or netting 16, and 90 in the opposite end of the door is formed a passage 17, of sufficient size to permit the chicks to enter and leave the house but which is not large enough to allow the hen to pass through. When the door is in place with 95 the ventilating opening at the lower end, neither the chicks nor the hen can leave or enter the house, the screen opening 15, being provided to admit fresh air to the lower portion of the coop, thus driving the foul air 100 out through the ventilating apertures 5, in the flanges at the top of the house while preventing the entrance of rats or other pests. When the door is in place with the passage 17, at the lower end, the chicks will be permitted to leave and enter the house while the hen will be confined therein. 105

The run or yard of the coop comprises sides 18, formed of wire netting, the upper and lower edges and one end of which are 110 bound or covered by metal strips, as shown. The strips at the outer ends of the sides have

formed thereon locking flanges 19, with which are adapted to be engaged similar flanges formed on the side edges of the end piece 20 of the yard or run, said end piece 5 20 being preferably formed of sheet metal. In the front end piece 20 is formed a door opening or passage 21, which is adapted to be closed by the door 13, when the same is not in use to close the door opening in the 10 house, or if desired, a separate door may be provided to close the opening in the end of the run. The yard or run is adapted to be closed by a removable cover section 22, formed of netting, bound around the edges 15 with metal strips having downwardly projecting retaining flanges 23, whereby the cover is removably held in place over the yard. By thus connecting the parts of the yard and house together, said parts may be 20 readily separated for cleaning or for packing to facilitate the storing or shipping of the same.

From the foregoing description taken in connection with the accompanying drawings, the construction and operation of the invention will be readily understood without requiring a more extended explanation.

Having thus described my invention, what I claim is:

30 A knockdown coop comprising side, front

and rear sections separably connected at the corners of the coop, upwardly and outwardly inclined flanges on the upper ends of the side and rear sections, said flanges having a plurality of ventilating apertures therein, 35 the front section having an inwardly and downwardly inclined top-supporting flange, a top having inturned flanges on its opposite side edges for slidable engagement with the flanges on said side sections, the flanges on 40 said top being narrower than those on the side sections to leave the ventilating apertures in said side-section flanges exposed, a downturned flange on the rear of said cover to form a stop for engagement with the 45 flange on the rear section, said top resting at its front on the flange of the front section and having its front edge extended beyond the front section, and a floor detachably mounted in said coop, said front section having a door opening provided with a suitable closure, said front section also having ventilating openings at the lower part thereof.

In testimony whereof I have hereunto set my hand in presence of two subscribing witnesses.

CHARLES LYMAN.
